UNITED STATES PATENT OFFICE.

JOSEPH DAVING, OF NEW YORK, N. Y.

DESIGN FOR A CASE AND DIAL FOR A WRIST-WATCH.

52,764.

Specification for Design.

Patented Dec. 17, 1918.

Application filed March 20, 1918. Serial No. 223,668. Term of patent 7 years.

To all whom it may concern:

Be it known that I, JOSEPH DAVING, a citizen of the United States, residing in the city of New York, county of New York, and State of New York, have invented a new, original, and ornamental Design for a Case and Dial for a Wrist-Watch, of which the following is a specification, reference being had to the accompanying drawing, forming part thereof.

Figure 1 shows a plan view of a case and dial of a wrist watch, illustrating my new design.

Fig. 2 shows a side elevation of the watch case.

What I desire to claim is:

The ornamental and original design for a case and dial for a wrist watch as shown in the annexed drawings.

JOSEPH DAVING.
